UNITED STATES PATENT OFFICE

136,881

DESIGN FOR A SMOKING PIPE

Charles Rubin, New York, N. Y.

Application October 7, 1942, Serial No. 108,448

Term of patent 14 years

To all whom it may concern:

Be it known that I, Charles Rubin, a citizen of the United States of America, residing in the Borough of Bronx, city of New York, county of Bronx, and State of New York, have invented a new, original, and ornamental Design for a Smoking Pipe, of which the following is a specification, reference being had to the accompanying drawing, forming a part thereof.

Figure 1 is a view in perspective of a smoking pipe showing my new design.

Figure 2 is an elevational view of Figure 1.

Figure 3 is a bottom plan view of Figure 2.

Figure 4 is a top plan view of Figure 2.

Figure 5 is an enlarged horizontal sectional view as seen from the plane 5—5 on Figure 2.

Figure 6 is an end elevational view as might be seen from the right of Figure 6.

The dominant features of my design reside in the portions shown in full lines in the drawing.

The characterizing features of my design for the smoking pipe illustrated reside in the bowl elongated in the direction of the pipe stem and in the flat panels on the sides of the bowl having vertical and parallel side edges as shown.

I claim:

The ornamental design for a smoking pipe, as shown and described.

CHARLES RUBIN.
